UNITED STATES PATENT OFFICE.

CHRISTIAN G. SCHNEIDER, OF WASHINGTON, DISTRICT OF COLUMBIA.

IMPROVEMENT IN CHAMBER-BUCKETS.

Specification forming part of Letters Patent No. 35,841, dated July 8, 1862.

To all whom it may concern:

Be it known that I, CHRISTIAN G. SCHNEIDER, of Washington city, in the District of Columbia, have invented an Improvement in Chamber-Buckets; and I do hereby declare that the following is a full and exact description thereof, reference being had to the accompanying drawings, and to the letters of reference marked thereon:

In the accompanying drawings, Figure 1 is a top view of my improved chamber-bucket, (when the cover is off the same,) showing the form and arrangement of the offsets D D; Fig. 2, a vertical section of the same, (when the cover is fitted and secured in place,) through the line x x of Fig. 1, showing the arrangement of the handle G, spring m, and cross-bar K, in connection with the flanged head of the vessel; Fig. 3, a vertical section of said vessel, (with the cover off,) through the line y y of Fig. 1, giving a side view of the stop N and notches n n in the offset of the flanged head; Fig. 4, an underneath view of the cover E of said vessel, showing the form and proportions of the cross-bar.

Similar letters indicate the same parts in each of the drawings.

It has been found necessary to obtain a chamber-bucket which will afford an easy seat to an invalid, and which will admit of being easily and readily covered or uncovered, and yet be so closed by the cover as to prevent the escape of its contents in any form. My improved chamber-bucket satisfies perfectly these requirements.

To a metallic vessel of suitable size and shape, A, an annular head or rim, B, is closely secured. This annular head B is furnished with a continuous outwardly-curving flange, C, and also with two opposite horizontal crescent-shaped plates or offsets, D D, which project from equal and opposite portions of the inner upper edge of this annular head B. These offsets D D are limited in length and width, so as to leave the mouth of the vessel as open as possible, and their relative proportions are about as represented in the drawings, Fig.

1. Upon this flanged annular head or rim B a metallic cover, E, Figs. 2 and 4, is made to fit closely and accurately by a water and gas tight beveled ground-in joint, e, Fig. 2, the beveled edge of the cover terminating in a narrow projecting flange, A, Figs. 2, 3, 4, which

finishes the joint more perfectly and securely and causes it instantly to fit and adjust itself in place when required. The shank F of the handle G, Fig. 2, passes loosely through the center of the cover E, Fig. 2, and is secured at its lower end to the center of a horizontal transverse metallic bar, K, Fig. 4. This transverse bar K is held closely against the sectional ribs L L on the under side of the cover, Fig. 4, at their point of intersection in the center by an india-rubber spring, m, which surrounds the shank F of the handle G between the upper side of the cover E and a shoulder on the said shank, Fig. 2.

The ribs L L are introduced in order to furnish a proper bearing for the transverse bar K on a plane even with the edge or rim of the cover. This transverse bar K is of such a length that when the cover is placed upon the annular head B of the vessel the extremities of the bar may pass beneath the projecting plates or offsets D D. Stops N N, Figs. 2 and 3, project downward from the central portion of these offsets, and notches or depressions n n are formed on each side of the same in a rim or flange which increases in width from either end of the offsets to their central stops, N, Fig. 3.

The cover being placed upon the annular head of the vessel, by turning the handle G the extremities of the transverse bar K pass beneath the offsets D D, and being drawn down as they move toward the center by the increasing width of the flanges on the under side of said offsets D D compress the rubber spring m, Fig. 2. The reaction of this spring will hold and secure the extremities of said bar when arrested by the stops N N firmly in the notches n n on either side thereof, and thus retain the cover tightly upon the head of the vessel. The vessel being upon the floor, pressure is readily applied to the handle sufficient to overcome the resistance of the spring and allow the extremities of the bar K to be released from the notches n n on the under side of the offsets D D and the cover to be easily lifted off.

A suitable handle, O, Fig. 3, is fastened to the side of the vessel, near the bottom of the same, at a point at a right angle with a line passing through the stops N N of the offsets D D to facilitate the removal of its contents.

The outwardly-curving flange C serves as a

hold or handle to the vessel when the cover is off, and, in combination with the plates or offsets D D, forms a comfortable seat to the vessel when used as a chamber-pot.

The vessel may be made of copper, tin, or other suitable material, and of any desirable size or shape.

Having thus fully described my improved chamber-bucket, what I claim therein as my invention, and desire to secure by Letters Patent, is—

Securing the cover E to the annular head or top B of the vessel by means of the handle G,

the cross-bar K, which is secured to the lower end of the shank F of said handle, the spring m, which embraces the said shank of the handle above the cover, and the offsets D D from opposite sides of the inner periphery of the said ring-shaped top B of the vessel when the said parts are arranged and are made to operate substantially in the manner and for the purpose herein set forth.

CHRISTIAN G. SCHNEIDER.
